United States Patent Office.

EDWIN C. HIESTER AND GABRIL O. HIESTER, OF READING,
PENNSYLVANIA.

Design No. 4,903, dated May 16, 1871.

DESIGN FOR A SASH-HOLDER.

The Schedule referred to in these Letters Patent and making part of the same.

To all whom it may concern:

Be it known that we, EDWIN C. HIESTER and GABRIL O. HIESTER, of the city of Reading, county of Berks and State of Pennsylvania, have invented a new and original Design for a Metallic Sash-Fastener; and we do hereby declare the following to be an exact description thereof, reference being had to the accompanying drawing and to the letters of reference marked thereon making a part of this specification, in which—

Figure 1 represents a perspective view of the design of fastener.

Figure 2 shows a side view of the same.

The nature of our invention consists in an oval casting of any kind of metal, having a semicircular slot at one end, with circular apertures, from which apertures the slot is continued to the other end of the plate, with a flange surrounding the plate.

A represents the metallic plate, with its flange B surrounding it;

C is the semicircular slot;
D D, the round apertures;
E E, the extension ends of the slot; and
B, the flange surrounding the plate.

The fastener is fastened by a screw, G, to the window-sash, the screw passing through the slot E, and the side or flange B of the fastener resting against the frame of the window, thus fastening or holding the sash to the frame.

What we claim as our invention, and desire to secure by Letters Patent, is—

The design for a metallic sash-fastener, as shown.
EDWIN C. HIESTER.
GABRIL O. HIESTER.
